UNITED STATES PATENT OFFICE.

CHARLES R. CRANE, 2D, OF CHICAGO, ILLINOIS, ASSIGNOR TO CRANE CO., OF CHICAGO, ILLINOIS, A CORPORATION OF ILLINOIS.

DESIGN FOR A LAVATORY.

Application filed July 22, 1927. Serial No. 22,843. Term of patent 14 years.

To all whom it may concern:

Be it known that I, CHARLES R. CRANE, II., a citizen of the United States, residing at Chicago, in the county of Cook and State of Illinois, have invented a new, original, and ornamental Design for Lavatory, of which the following is a specification, reference being had to the accompanying drawing, forming part thereof.

In the drawing:

The figure is a perspective view of a fixture showing my new design.

The dominant feature of the design is the three-step drop of the rim in association with the two-step drop at the bottom of the pedestal.

I claim:

The ornamental design for a lavatory as shown and described.

CHARLES R. CRANE, II.
